UNITED STATES PATENT OFFICE.

ROBERT PARRY, OF ALPINE, COLORADO.

ORE-CONCENTRATOR.

SPECIFICATION forming part of Letters Patent No. 243,607, dated June 28, 1881.

Application filed March 29, 1881. (Model.)

To all whom it may concern:

Be it known that I, ROBERT PARRY, of Alpine, in the county of Chaffee and State of Colorado, have invented a new and Improved 5 Ore-Concentrator, of which the following is a specification.

The invention consists in diaphragm-moving bars combined with adjustable tops, whereby the motions of the diaphragms may be increased or diminished, as hereinafter described.

Figure 1 is a plan of the device with parts removed and parts broken away to exhibit other parts. Fig. 2 is a side elevation, partly in section, on line $x-x$, Fig. 1. Fig. 3 is a side 15 elevation with parts removed, partly in section, on line $y-y$, Fig. 1. Fig. 4 is a sectional end elevation on line $z-z$, Fig. 1.

Similar letters of reference indicate corresponding parts.

20 In the accompanying drawings, A represents the jig-box, which may consist of any number of compartments, D, and in this instance consists of three, that are separated from each other by the vertical partitions B B. 25 Each compartment D is partially subdivided by a longitudinal vertical partition, C, that extends downward from the top of the box A. Thus, in plan, six rectangular openings are formed, three on each side of the partition C. 30 In each of the openings on one side of the partition C is fixed a horizontal partition, E, that fills said opening and is provided with a central aperture, a , covering which is an elastic diaphragm, F, of leather, rubber, or the like, 35 that is secured on top of the partition E by bolts b , or other suitable device. Above the diaphragms F beams G are secured longitudinally between the partitions B B and ends of the box A, and serve to support the journal-boxes G' of the upright bars H, whose lower enlarged ends rest on the centers of the diaphragms F, and whose upper ends or tops, c , are within reach of the cams L. The tops c of the bars H are adjustable, so as to lengthen 40 or shorten said bars H, and thereby increase or diminish the movements of the diaphragms F, and are secured thereon by set-screws d .

45 On the top of the box A are fixed standards K, that support the shaft L, which carries the 50 cams L'.

L² represents the pulley keyed on the shaft L, through which power is applied to revolve the shaft L, for the purpose of bringing said cams L' in contact with the tops of the bars

H, and thereby giving motion to the dia- 55 phragms F.

The lower part of each compartment D is furnished with sloping sides ff and back g , which come to a point in the bottom of the box A, and at this point an ore-discharge opening, 60 h , is made in the front of the box A, and closed by a valve, h' .

In the openings on the opposite side of the partitions C from the diaphragms F the sieves M are fixed at a higher elevation than said 65 diaphragms F, said sieves M being composed of a barred frame, m , and screen n . An opening, N, for the overflow of the water from the concentrator is made in one end of the box A, above the level of the sieves M, and on the 70 same side with them of the partitions C.

It is designed to introduce water for the operation of the concentrator at any convenient point in the lower part thereof.

In operating this device the compartments 75 D thereof are filled with water, and the shaft L is put in motion, so that the cams L' shall strike the bars H, and thus impart motion to the diaphragms F, whereby an intermittent stream of water is forced upward through the 80 sieves M. Ore being now fed upon said sieves M will, according to its specific gravity, settle on and pass through the said sieves M, and falling will be discharged through the opening h , while the lighter gangue will be 85 carried off by the upward flow and pulsations of the water through the overflow N. The upward movements of the diaphragms F, being due to their elasticity and the upward pressure of the water beneath them, are so com- 90 paratively slow that they cause too feeble a current down through the sieves M to draw the gangue down through them; hence the concentration of the ore is made very thorough.

95 Having thus fully described my invention, I claim as new and desire to secure by Letters Patent—

In an ore-concentrator, the combination, with the diaphragm-moving bars H, of the adjustable tops c , substantially as herein shown and described, whereby the motion of the diaphragm may be increased or lessened, as set forth.

ROBERT PARRY.
